UNITED STATES PATENT OFFICE.

JAMES NATHAN BATTs, OF COAL VALLEY, WEST VIRGINIA.

SCRUBBING-MACHINE.

SPECIFICATION forming part of Letters Patent No. 368,052, dated August 9, 1887.

Application filed September 18, 1886. Serial No. 213,925. (No model.)

To all whom it may concern:

Be it known that I, JAMES NATHAN BATTs, a citizen of the United States, residing at Coal Valley, in the county of Fayette and State of West Virginia, have invented a new and useful Improvement in Scrubbing-Machines, of which the following is a specification.

My invention relates to an improvement in scrubbing-machines; and it consists in the peculiar construction and combination of devices, that will be more fully set forth hereinafter, and particularly pointed out in the claims.

In the drawings, Figure 1 is a perspective view of a scrubbing-machine embodying my improvements. Fig. 2 is a vertical longitudinal sectional view of the same.

A represents a car, which is provided on its under side with cross-bars B. To the ends of the said cross-bars, on the under sides of the same, are pivoted casters C, in which are journaled rollers D, that bear upon the floor and support the car and enable the latter to be moved in any direction. In the rear portion of the car is made a seat, E, for the operator, and in the front end of the car is a compartment or box, F, which is water-tight and is adapted to receive the suds to be used in scrubbing the floor. This box or compartment is provided on its upper side with a hinged 30 lid, G.

H represents a crank-shaft, which is journaled in bearings I, that are secured to the upper edges of the car at a suitable distance in front of the seat E, and to one end of the crank-shaft is attached a crank-wheel, K.

L represents a rock-shaft, which is journaled in bearings M at the front end of the car, near its lower side. The said rock-shaft is provided at its center with a crank, L', and at one end with a crank-arm, L''. This latter is connected to the crank-wheel K by means of a pitman-rod, N, which is provided near its upper end with a slot, M', in which works the crank-pin O, that projects from the crank-wheel K.

From the foregoing description it will be readily understood that when the crank-shaft H is rotated the shaft L will be rocked or oscillated.

The function of the slot M' is to cause the shaft L to "dwell" or remain stationary twice

at each rotation of the crank-wheel while the crank-pin O is passing the dead-center, to the end that the scrubbing-brush hereinafter described will be caused to rest on the floor during a short period at the end of each stroke. 55

R represents a spring-rod, which is attached at its inner end to the crank L'. This spring-rod is guided by a keeper, S, on the front end of the car, and projects forwardly therefrom, 60 and the outer end of the spring-rod is provided with a transverse notch, R'.

T represents a scrubbing-brush, on the upper side of which is made a transverse recess, T', adapted to receive the front end of the spring-rod, and the said scrubbing-brush is also provided on its upper side with a hinged strap, T'', which is adapted to close over the front end of the spring-rod and rest in the notch thereof, and the free end of the strap is secured to the scrubbing-brush by means of a catch, T''. By this means it will be readily understood that the scrubbing-brush may be firmly attached to the front end of the spring-arm or disengaged therefrom. In the lower 75 side of the suds-box F is a pipe, U, which projects forwardly from the car, and the inner end thereof is open and communicates with the interior of the suds-box. A stop-cock, V, is provided for the said pipe, and the stem V' 80 thereof projects upwardly through the cover of the suds-box, and is provided at its upper end with a suitable handle, by means of which the stop-cock may be turned so as to permit water in the suds-box to be discharged upon 85 the floor through the pipe U.

The operation of my invention is as follows: In order to scrub a floor a suitable quantity of suds is poured into the suds-box and the scrubbing-brush is attached to the spring-rod. 90 The operator is then seated on the seat E and grasps the crank-shaft H and rotates the same, thereby communicating an oscillating motion to the shaft L and causing the scrubbing-brush to be reciprocated back and forth in front of the car in contact with the floor. A suitable quantity of suds is discharged upon the floor through the pipe U, and the reciprocating motion of the scrubbing-brush is maintained a sufficient length of time to cause it 95 to thoroughly scrub the floor at that point. A pushing pole or lever is grasped by the oper-

ator in the car, and the end thereof is rested against the floor or wash-board, and by pressing upon the same the car may be moved to any point of the floor desired.

5 From the foregoing description it will be readily understood that the operator is entirely protected from contact with the floor while the scrubbing is being done, thus rendering it impossible for her feet to get wet, and avoiding the danger of contracting colds or rheumatism.

Having thus described my invention, I claim—

15 1. The combination of the car, the crank-shaft II, journaled thereto and having the crank-pin O, the rock-shaft L, the scrubbing-brush connected thereto and operated thereby, the said rock-shaft having the crank L², and the pitman N, connecting the latter with the 20 crank-pin O, and having the slot M, in which the said pin slides, for the purpose set forth, substantially as described.

2. The combination of the car, the rock-shaft journaled thereto and having the cranks 25 L' and L², the bar R, pivoted to the crank L' and having the scrubbing-brush at its outer end, and the crank-shaft II, journaled to the car and connected to the crank L² of the rock-shaft, whereby the latter may be oscillated, 30 for the purpose set forth, substantially as described.

3. The combination of the car having the supporting-rollers, the suds-box, and the seat, the rock-shaft L, journaled to the car and having the cranks L' and L², the rod R, connected to the crank L' and having the scrubbing-brush at its outer end, and the crank-shaft II, journaled to the car and having the crank-wheel K, and the pitman-rod connecting the said crank-wheel with the crank L² of the rock-shaft, for the purpose set forth, substantially as described.

4. The combination, in a scrubbing-machine, of the rock-shaft having the crank-arm, and the spring-rod R, attached to the said crank-arm and carrying the scrubbing device, substantially as described.

5. The combination of the rod R, having the notch R' at its front end, with the scrubbing-brush having the notch T' to receive the 50 front end of the bar, and the locking-strap T², to enter the recess R' and secure the scrubbing-brush to the spring-bar, substantially as described.

In testimony that I claim the foregoing as 55 my own I have hereto affixed my signature in presence of two witnesses.

JAS. NATHAN BATTs.
